UNITED STATES PATENT OFFICE.

WILLIAM H. BROCK, OF CORONA, NEW YORK.

BOX-NAILING MACHINE.

SPECIFICATION forming part of Letters Patent No. 230,230, dated July 20, 1880.

Application filed April 5, 1880. (Model.)

To all whom it may concern:

Be it known that I, WILLIAM H. BROCK, of Corona, in the county of Queens and State of New York, have invented an Improvement in 5 Box-Nailing Machinery, of which the following is a specification.

Before my invention numerous devices had been made for aiding in the manufacture of boxes. In some instances the parts of the box 10 have been held firmly in their proper relative positions while the nails have been driven by hand. In other instances the nails have been supplied automatically and driven into the wood by a plunger or punch.

15 My invention is available in the manufacture of boxes where one particular size of box is required. I employ a form that corresponds to the internal measurements of the box. The sides of the box are supplied to the respective 20 sides of this form. Spring-claws act to carry the sides of the box down with the form, and the nails are driven automatically. The form then rises, and the additions of the side pieces for the next box cause the box that has been 25 nailed to be held while the form draws partially out of the nailed box. The sides of the second box are nailed together as the form is carried down, and the sides of the third box hold those previously nailed, and as the form 30 is drawn off the first box drops upon a belt and is carried to an elevating-shoe, where an attendant lifts the box and applies the bottom, and nails the same upon the sides, either by automatic mechanism or by hand.

35 In the drawings, Figure 1 is a vertical section transversely of the machine. Fig. 2 is a longitudinal section, and Fig. 3 is a cross-section at the line $x x$.

The bed a stands on suitable legs a' , and 40 upon it are the columns b , that support the form-carrier c and hoppers or chutes $d d' e e'$.

The standards c' support the driving-shaft f , and suitable power is applied to revolve the same.

45 f' is the driving-pulley, and 4 is a clutch for starting and stopping the machine.

The form g is of the same size as the inside measurement of the box, and it slides freely in, but it is guided vertically by the form-carrier c , and there is a counter-weight, g' , within 50 the hollow form, and cords or chains 22 pass

from the counter-weight over pulleys on the shaft f , and connect to the cross-bar 3, so that the form can be moved up or down with but little power.

In order to draw the form up I make use of a gear-wheel, h , upon the shaft f and a rack, k , that is hinged at its lower end to the upper end of the form, and such rack has a handle or lever, k' , by means of which it is brought 60 into gear with the teeth on the wheel h . The revolution of the shaft f turns the wheel, and its teeth act upon the rack and raise the form to the proper height, after which the rack is disconnected from the teeth of the barrel. This 65 is done after each box has been nailed, so as to draw the form out of the box, as before mentioned.

The wood is sawed up into the proper widths and lengths, and supplied in a vertical position into the hoppers, those marked d receiving the side pieces and those marked e the end pieces, and there is the necessary distance between the inner ends of the hoppers or chutes and the form for the wood to pass down.

75 There are spring dogs or claws 6 in the form that spring out over the upper edges of the wood, and they carry the four pieces composing the sides and ends of the box down with the form as the form is moved down, and the 80 nails are driven into the wood to fasten the sides and ends together.

The means for applying the nails are of any usual or desired character. There are four of these at the angles of the box. Each has a 85 hopper, l , a separator, 8 , to let one nail at a time pass down from the hopper, and a punch, g , to drive the nail.

Each punch is operated by a crank, m , that is at the end of a short shaft supported in the 90 arms n , that project from a cross-bar above the columns b , and from cranks 19 at the ends of the short shafts there are connecting-rods 10 to cranks 11 at the ends of the driving-shaft f , so that all the four nailing appliances are 95 operated simultaneously.

It will be apparent that the punches are operated to drive the nails once for each revolution of the shaft f , and as the punches are being drawn back to take another nail I operate 100 the mechanism that carries down the form and the four sides of the box so as to bring

them into position for the insertion of the next nails. I effect this by the action of an eccentric, 12, on the shaft *f*, that moves up and down a ratchet-bar, *o*, the teeth of which take into 5 the cross-bar 3' of the form. This eccentric forces the ratchet-bar *o* down as the nail-punches draw back, and moves the form and box sides down. The ratchet-teeth correspond to the distance between one nail and the next. 10 The ratchet-bar *o* has a lever-handle, *o'*, by which the attendant brings it into action when the nailing is progressing, and when the attendant releases his hold upon the lever the rack-bar swings out of action by the weight 15 of the lever.

If desired, two levers, rack-bars, and eccentrics may be used, as shown, to act simultaneously in forcing down the form at both sides of the center thereof to insure parallelism of 20 movement; or the rack-bars may be made with teeth of different sizes, so as to vary the distances between the nails, as required.

From the foregoing it will be understood that the sides of the box are firmly nailed together on the form, and that the friction between the wood and the form prevents the box dropping off. When the sides of one box have 25 been nailed together the four pieces of wood closing around the form from the chutes hold such box down while the form is raised, because the upper edges of such four pieces are beneath the lower edges of the form-carrier *e*, and thereby the form partially draws out 30 from the box, leaving the box projecting below it. When the form is drawn up the second time it draws entirely out of the box, and said box drops upon the belt *r*. The opening in the bed *a* allows the box to pass freely 35 through the same, and the belt or carrier *r*, traveling in the direction indicated by the arrow, carries the box to the shoe *t*, that is made with stops 15, that arrest the endwise movement of the box, and said shoe is guided by the vertical slide-bars *u*, and is lifted by the 40 treadle *v*, so that when the four sides of the box have been received into the shoe an attendant lifts the shoe, carrying the box up into 45 an opening in the bed *a*, at which place the bottom piece of the box is applied and nailed 50 on. This nailing may be done by hand; but I have shown the sets of punches *w* and hoppers 21 for the nails, said punches *w* being

operated by the crank-arms 22, rock-shaft 23, crank 28, and connecting-rod 24 to one of the cranks 19. After the bottom has been nailed 55 upon the box the treadle is released, the box lowered and removed.

I claim as my invention—

1. In a box-nailing machine, the combination, with the form, of four hoppers or chutes 60 to supply the four sides of the box, and nail-driving mechanism applied to drive the nails simultaneously at the four angles, substantially as set forth.

2. In a box-nailing machine, the combination, with the form, of the form-carrier, the counter-balance within the hollow form, four hoppers or chutes, dogs for carrying down the wood, nailing mechanism, and a toothed rack and actuating-eccentric for moving the form, 70 substantially as set forth.

3. In a box-nailing machine, the combination, with the form, of the driving-shaft *f*, eccentric 12, toothed rack-bar *o*, and lever *o'*, for moving the same, substantially as set forth. 75

4. In a box-nailing machine, the combination, with the vertically-sliding form, of the rack *k*, lever *k'*, and gear-wheel *h*, substantially as set forth, to raise up the form.

5. In a box-nailing machine, the combination, with four nail-driving appliances, of the connecting-rods 10, cranks 11 19 *m*, and driving-shaft *f*, for actuating the drivers simultaneously, as set forth.

6. In a box-nailing machine, the combination, with the form and mechanism for nailing the four sides together, of a belt or carrier for receiving the partially-formed box, a shoe and lever for raising the same, and a bed with a guide-opening to steady the parts while the bottom is applied and nailed on, as set forth. 85

7. The combination, in a box-nailing machine, of a form around which the four pieces of wood are supported while being nailed, four automatic nail-driving devices at the respective corners, and mechanism for actuating the nail-drivers, substantially as specified. 95

Signed by me this 25th day of March, A. D. 1880.

WILLIAM H. BROCK.
